(57) CLAIM

The ornamental design for a vending machine housing; as shown and described.

DESCRIPTION

FIG. 1 is a perspective view of the vending machine housing;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines illustrating the vending machine are for illustrative purposes only and form no part of the claimed design.
